UNITED STATES PATENT OFFICE.

ELIAS JOSEPH, OF WASHINGTON, DISTRICT OF COLUMBIA.

PATTERN HOLDER, SAVER, AND HANGER.

1,249,411.

Specification of Letters Patent. Patented Dec. 11, 1917.

Application filed March 10, 1917. Serial No. 153,905.

To all whom it may concern:

Be it known that I, ELIAS JOSEPH, a citizen of the United States, residing at Washington, in the District of Columbia, have invented certain new and useful Improvements in Pattern Holders, Savers, and Hangers, of which the following is a specification.

This invention relates to a pattern saver, holder, and hanger, in the use of which garment patterns, either singly, or in full sets for a person, may be secured in a protected, segregated manner, for ready future reference and use.

Patterns, singly or in sets, as for example of the coat, vest and trousers, are designed after initial use to be kept together for future use and reference, and the nature of the material from which such patterns are made, renders it difficult to keep such in proper order without damage, and yet readily accessible when desired for use.

The present invention contemplates a holder, preferably constructed from a single blank, in which the patterns may be readily and quickly secured, the holder providing a structure in which the patterns are fully protected, and by which the patterns may be suspended in a conveniently accessible manner, so that any desired pattern, or set of patterns may be quickly secured, when desired for reference or reuse, without disturbing other patterns.

The improved holder is preferably made of substantial material, the blank being formed for holding to provide a back and face section, between which the pattern or patterns are to be secured; the blank being also formed to provide an integral hook, by means of which the holder with the contained patterns may be suspended from a convenient support, for convenient and ready accessibility.

The invention will be described in the following specification, reference being had to the accompanying drawings, in which:

Figure 1 is a plan view of the holder, a set of patterns being shown therein.

Fig. 2 is a view of the blank, in complete form, prior to folding.

Fig. 3 is a broken plan, showing a slightly-modified form of holder.

Fig. 4 is a plan view of a somewhat different form of holder.

The improved holder is constructed of a single blank 1, approximately rectangular

in outline, and scored or otherwise arranged for folding on the transverse median line 2. The relatively upper fold of the blank constitutes the face or front section 3 of the holder, while the lower fold constitutes the rear or back section 4 of the holder.

The upper fold or face section 3 of the holder is cut on a curved line 5, terminating at its ends at the main line of fold 2, the portion 6 of the blank, within the line of cut 5, being free of the main fold line scoring 2. The portion 6 is designed to remain in the plane of the lower or back section 4 of the holder, and is formed to provide a hook 7, the material beyond the hook, within the line of cut being discarded. When the sections are folded, as in Fig. 1, the hook 7 extends above the upper edge of the holder sections, to provide a means by which the holder with the contained patterns may be suspended.

If the holder is made of a material liable to fracture under strain, as cardboard or the like, the support-engaging edge of the hook may be reinforced, as by a metallic strip 8, which strip is adapted to overlie and cover said hook edge, to receive the wear and strain and protect the hook proper.

The sections are preferably provided with clamping means, such as edge clips 9, pivotally connected to one section, as the back 4, and having comparatively long extensions 10 to overlie and bear upon the other section. The bearing portions 10 of the clips are comparatively long, relatively considered, so as to provide a firm clamping action and prevent buckling or bending of the sections when in use.

The sections 3 and 4 are each formed near their lower free edges, and approximately centrally of their widths, with an opening 11, the said openings registering when the sections of the holder are in closed relation. These openings permit the use of a fastener, as an ordinary paper fastener 12, to be passed through the opening in the back 4, through the patterns 13 to be secured in the holder, and through the opening in the front 3, after which the fastener may be opened to secure the parts together.

The back section 4 is preferably formed within the plane of the cut out portion of the face section, with an opening 14, providing for the use of a similar fastener to that previously described, when storing small pat-

terns, or when it is desired to secure the patterns at two remote points within the holder.

In the form shown in Figs. 1 and 2, the holder outline is square at the corner remote from the hook, the similar opposite corner being rounded. The corners adjacent the hook are cut out, as at 15 and 16, so that the general outline of this form of the holder is that of a coat front.

10 In Fig. 3 the construction is similar to that described, the variation being secured in having both corners remote from the hook square, and the face sections corners adjacent the hook square, with the back section 15 cut out. In Fig. 4, the variation is again in the form or outline, all corners being square.

The patterns are secured between the sections of the holder, and are thus held in an orderly flat relation. They are thoroughly 20 protected and yet readily and conveniently accessible. The holder with the contained patterns may be suspended from a hook, bar, or other support, by means of the hook 7, or may be stored in convenient piles. In either 25 event the desired pattern is conveniently selectable from the other patterns so stored, without necessity of search and the handling of many patterns other than those desired.

The outer surface of the front section 30 may, and preferably is printed or otherwise marked to indicate blank spaces or lines, on which data as to the particular pattern may be written. A convenient identification and description of the contained pattern is thus 35 on the holder for the convenience of the user.

Of course the use of any material is contemplated, and furthermore, it is to be understood, that so long as the salient features disclosed are used, I consider the construction 40 of the holder in any convenient or desirable outline form, and any variation in the size, as clearly within the spirit of the present invention.

It is apparent from the above description 45 that it is not particularly important that the improved pattern holder be constructed in hingedly connected or folding sections, as

the front and back sections may be made separate, and used as in a preferred form.

Furthermore, the back section may, in the 50 event that the sections become detached used to support and in a measure protect the patterns, by securing the patterns thereto by paper fasteners or the like through the 55 holes 11.

Furthermore, in all the forms described it is apparent that if desired the back section may be provided with lines for suitable data, as described in connection with the front section, and that the sections may be reversely 60 folded from that previously described, with the present front section becoming the back section. This provides for a double use of the device.

65 What is claimed is:—

1. A pattern holder constructed of a flat rectangular strip adapted to be folded on the transverse median line to provide substantially similar flat contacting front and back sections, the front section portion being cut 70 out prior to folding to leave a central part in the plane of and rigid with the back section in folding, said cut-out portion being formed into a supporting member by shaping and reducing said central part, whereby an appreciable opening is formed in the front section adjacent and below the line of fold. 75

2. A pattern holder constructed of a flat rectangular strip adapted to be folded transversely to provide substantially similar flat 80 contacting front and back sections, the front section being cut out prior to folding to leave a central part in the plane of and rigid with the back section in the folded form, said cut-out part being further reduced and formed 85 into a supporting member, thereby leaving an opening in the front section, both sections being formed with registering holes to receive independent fasteners to pass through both sections and the material within the 90 holder.

In testimony whereof, I affix my signature.

ELIAS JOSEPH.
